UNITED STATES PATENT OFFICE.

HJALMAR G. CARLSON, OF WORCESTER, MASSACHUSETTS, ASSIGNOR TO ROCKWOOD SPRINKLER COMPANY OF MASSACHUSETTS, OF WORCESTER, MASSACHUSETTS, A CORPORATION OF MASSACHUSETTS.

METHOD OF FORMING A SHEET-METAL NUT.

1,171,702.

Specification of Letters Patent. Patented Feb. 15, 1916.

Application filed April 15, 1910. Serial No. 555,717.

To all whom it may concern:

Be it known that I, HJALMAR G. CARLSON, a citizen of the United States, residing at Worcester, in the county of Worcester 5 and Commonwealth of Massachusetts, have invented a new and useful Improvement in Methods of Forming a Sheet-Metal Nut, of which the following is a specification accompanied by drawings, forming a part of the same and illustrating the method of carrying 10 my invention into effect.

The object of my present invention is to provide a method of forming sheet metal blanks into cup shaped articles such as nuts 15 or the like.

My improvements are especially adapted for the production of that class of articles which in cross section present outer and inner surfaces other than parallel. In the 20 accompanying drawings I have illustrated my invention as applied to the manufacture of nuts having the interior cylindrical to receive a screw thread, and having a polygonal exterior, in the present instance hexagonal, to receive a wrench, the completed nut being produced from a blank consisting of a cylindrical disk.

Referring to the accompanying drawings, Figure 1 is a view of a disk shaped blank 30 from which a hexagonal nut is to be produced. Fig. 2 is an edge view of the same. Fig. 3 is a plan view of a hexagonal shaping die. Figs. 4 and 5 represent the shaping die in sectional view and show blanks being 35 forced through the dies by the pressure of a cylindrical punch, the sections of Figs. 4 and 5 being represented on the planes of the broken lines 4—4, 5—5, Fig. 3, respectively. Fig. 6 is a perspective view of the blank 40 after it has been forced through the die represented in Fig. 3. Figs. 7 and 8 are top and side views respectively of the blank after it has been forced through the die represented in Fig. 3. Fig. 9 represents an end 45 view of the punch employed in connection with the several dies. Figs. 10 and 11 are vertical sectional views of a reducing die having a smaller aperture than that shown in Fig. 3, the sections being taken on planes 50 at right angles to each other, and representing a blank in its passage through the die. Figs. 12 and 13 are side and top views respectively of the blank after its passage through the die as shown in Figs. 10 and 11,

and Fig. 14 is a vertical sectional view of 55 a completed hexagonal nut which has been formed in accordance with my present invention.

Similar reference characters refer to similar parts in the different views. 60

My present invention is especially designed for the formation from a sheet metal blank of a hexagonal screw threaded nut, and therefore I have illustrated the invention in the accompanying drawings in connection with the manufacture of a nut of 65 that class. The blank from which the nut is formed consists of a circular disk 1 of sheet metal represented in plan view in Fig. 1, and in edge view in Fig. 2, the thickness 70 of the disk being determined somewhat by the proposed thickness of the walls of the nut. I employ a die 2 as shown in plan view in Fig. 3 having a cylindrical recess 3 at its upper edge suitable to receive the blank 1 75 and communicating with a hexagonal hole 4 in the die, whose diameter is less than the diameter of the circular recess 3. The circular recess 3 and the hexagonal hole 4 are connected by a tapering hexagonal section 5 to facilitate the passage of the blank when placed in the recess 3 through the hole in the die. In connection with the die 2 I employ a cylindrical punch 6 whose diameter corresponds with the required interior 80 diameter of the nut when completed. The disk shaped blank 1 is placed in the recess 3 of the die 2 and forced through the hexagonal hole 4 by means of the cylindrical punch 6 forming the shape shown in Figs. 6, 7 85 and 8, giving a hexagonal form to a portion of the exterior, but without substantial 90 change in the thickness of the blank.

The die 2 is of proper size with relation 95 to the punch 6 to enable the blank to be pressed into a cup shape, as shown in perspective view in Fig. 6, giving a cylindrical form to the interior wall at the bottom of the cup and a hexagonal form to the exterior of the cup at the top. To produce this result the blank is made to fill the space between the hexagonal walls of the die and the cylindrical surface of the punch on the plane of the broken line 5—5, Fig. 3, and as shown 100 in sectional view in Fig. 5, while the blank 105 at the hexagonal corners 7, Fig. 7, will be simply bent by its contact with the die. The cup shaped blank as shown in Figs.

6, 7 and 8 is then crowded through a second die 8, by the same cylindrical punch 6 or by a punch of equal diameter. The hexagonal opening 9 in the die 8 is smaller than that 5 in the die 2, by which the sides of the cup are drawn, causing a slight reduction in the thickness of the metal at the corners 10, Fig. 13, while the hexagonal sides 11 are still further reduced in diameter.

10 By the second drawing through the die 8 an elongation is made of the sides of the cup, thereby increasing its depth and forming the hexagonal outer surfaces of sufficient area to receive a wrench, as shown at 12, 12, 15 Fig. 12. The nut is then completed by trimming the edge 13 at right angles with the axis of the nut, forming the screw thread 14 and, if desired, forming a hole 15 through the bottom, as represented in Fig. 14.

20 I claim—

25 1. The method of shaping sheet metal, consisting in bending the peripheral portion of a sheet metal blank to form a substantially cylindrical portion, thus producing a cup, and simultaneously pressing the inner face of said portion into cylindrical

form and the outer face thereof into polygonal form.

2. The method of forming a polygonal nut, consisting in bending the peripheral portion of a sheet metal blank to form a substantially cylindrical portion, thus producing a cup, simultaneously pressing the inner face of said portion into cylindrical form and the outer face thereof into polygonal form, 35 and cutting threads in the inner cylindrical face of the cup to form the nut.

3. The method of forming a nut, consisting in bending the peripheral portion of a sheet metal blank to form a substantially cylindrical portion, thus producing a cup, simultaneously pressing the inner face of said portion into cylindrical form and the outer face thereof into polygonal form, cutting threads in the inner cylindrical face 45 thus formed, and forming an opening in the closed end of the cup.

Dated this fourteenth day of April 1910.

HJALMAR G. CARLSON.
